MUTILATED GEARING

Robert E. Clyne, Monroe Township,
Miami County, Ohio

Application March 30, 1948, Serial No. 17,937

4 Claims. (Cl. 74—435)

1

This invention relates to a mono-cycle gear clutch, that is, a mechanism for clutching a gear to a power means to impart a single cycle of rotation to the gear and particularly to such a device employed in a target throwing trap mechanism.

It is an object of this invention to provide such a structure capable of being remotely controlled to effect release of a target trap to project a target therefrom and to subsequently re-cock the trap, all with one rotation of a rotatable member.

It is a further object of this invention to provide such a structure employing a mutilated gear and in which means are provided to ensure positioning of the toothless portion of said gear adjacent a driving pinion between cycles of operation thereof.

It is a further object of this invention to provide, in a mutilated gear mechanism, safety means to prevent breaking of any of the gear teeth when the mutilated gear and driving pinion are first moved into mesh with each other.

It is a still further object of this invention to provide such a device that is simple in construction and operation with subsequent economy of manufacture.

Further objects and advantages of the invention will become apparent as the description proceeds in connection with the accompanying drawings, wherein,

Figure 1 is a sectional view through a protective housing generally provided for a target trap and showing an embodiment of the present invention, therein;

Figure 2 is a partial sectional view of the subject matter of this invention with power means omitted therefrom for clarity of illustration;

Figure 3 is a schematic wiring diagram of the circuits employed in the present invention;

Figure 4 is a side elevational view of the subject matter with certain parts broken away; and,

Figure 5 is a horizontal sectional view taken substantially along the axis of the large gear of Figure 4, but showing certain parts in elevation.

In Figure 1 of the drawings, numeral 1 indicates generally a target throwing trap of conventional construction wherein an operating member 2 may be actuated toward the left a short distance to release a spring loaded mechanism of the target trap to project a "clay pigeon" or other target into the air through the open side of the protective housing 3. Movement of the member 2 to the right, after release of the throwing mechanism operates on the target trap to re-cock the spring mechanism referred to.

The operating member 2 is shown as comprising a portion attached to the target trap, a portion attached to the mechanism indicated generally at 4, and an internally threaded sleeve 5

2

threadedly connected to adjacent ends of each of the portions referred to. The threaded sleeve 5 may be manipulated to effectively shorten or lengthen the operating member 2 for a purpose to be later described.

The mechanism 4 will now be described in greater detail. With particular reference to Figure 5, a base member 6 supports a pair of bushing brackets 7 in which anti-friction bearings 8 support a shaft 9 for rotation. Keyed or otherwise fastened to the shaft 9 for rotation therewith are a gear 10 and a crank arm 11. The gear 10 is provided throughout most of its periphery with gear teeth 12 (Fig. 4) but a predetermined sector of the gear 10, as indicated at 13, has the teeth omitted therefrom. Such gears are commonly known in the art as mutilated gears and hereinafter the term "mutilated gear" will be employed to define such a gear as just described.

A crank pin 14 is mounted on the free end of the crank arm 11 and is held thereto by a nut 15. The free end of the crank pin 14 has mounted thereon an adjustable second crank arm 16. The crank arm 16 is adjustable about the axis of the crank pin 14 and is held in adjusted position by a nut 17 threaded to the free end of the crank pin 14. The second crank arm 16 carries a second crank pin 18 at the free end thereof. The purpose of the second adjustable crank arm 16 will appear later.

The operating member 2 described in connection with Figure 1 is journaled at one end thereof to the crank pin 14 in any suitable manner, to be operated thereby.

The web portion 19 (see Fig. 2) of the gear 10 is provided with an opening 20 in which an abutment element 21 is mounted and held by means of a nut 22. The abutment element 21 projects laterally from the web of the gear 10. The right hand bracket 7, as seen in Figure 2, is provided with a fixed guide sleeve 23 projecting therethrough and having a slidable stop element 24 mounted therein. The slidable stop element 24 has a reduced portion 25 projecting from the right hand end of the guide sleeve 23 and surrounded by a compression spring 26. The compression spring 26 abuts at one end against a shoulder on the stop element 24 and at its other end against an inturned flange on the guide sleeve 23, all as clearly shown in Figure 2 of the drawings. The guide sleeve is so positioned that the spring 26 will urge the stop element 24 to the left so that its outermost end lies in the path of rotation of the abutment element 21 carried by the gear 10.

A stop pin 27 projects through the reduced portion of the stop element 24 and engages the outer end of the guide sleeve 23 to prevent the stop element 24 from being projected into contact with

the web of the gear 10 after its end has entered the path of movement of the abutment element 21. The reduced end portion of the stop element 24 is connected in any suitable manner to the armature 28 of a suitable solenoid indicated generally at 29.

The base 6 also supports guide means 30 so designed and shaped as to provide a rectilinear guideway for a carrier 31 slidably carried thereby. Mounted on the carrier 31 is a gear motor indicated generally at 32 and comprising an output shaft 33 on which a driving pinion 34 is keyed or otherwise attached. The guideway provided by the members 30 and the extent of movement of the carrier 31 thereon is such that the drive pinion 34 may be moved by said carrier into position to properly mesh with the teeth of the gear 10. If desired, the guideway just described may be provided with anti-friction means, such as ball or roller bearings.

A threaded rod 35 is attached in any suitable manner to the rear of the carrier 31 and slidably passes through an opening in a bracket 36 attached to the base 6. A pair of lock nuts 37 and a washer 38 on the threaded rod 35 provide an abutment between which, and the bracket 36, a compression spring 39 is confined. The compression spring 39 surrounds the rod 35 which latter also has a pair of lock nuts 40 thereon to limit the expansion of the spring 39 and consequently the movement of the carrier 31 to the left, as seen in Figure 4.

It will be apparent that the lock nuts 40 may be so adjusted that the carrier 31 will be urged by the compression spring 39 to a position where the pitch circle of the pinion 34 is substantially tangent to the pitch circle of the gear 10, which is the proper driving relationship for a pair of meshed gears. It will also be apparent that the carrier 31 is capable of movement to the right, as seen in Figure 4, against the pressure of the spring 39.

All of the parts are so relatively positioned and adjusted that the mid-portion of the toothless sector 13 of the gear 10 will be positioned adjacent the pinion 34 when the abutment element 21 is in engagement with the stop element 24. In this position, the pinion 34 can continue to rotate continuously without engaging any portion of the gear 10, and the gear 10 may thus remain stationary even though the motor 32 and pinion 34 are rotating continuously.

A tension spring 41 is attached at one end, as at 42, to the base 6 and at its opposite end to a swivel element 60 rotatably mounted on the second crank pin 18 described above. The second crank arm 16 will be so adjusted relative to the crank pin 14 that when the teeth of the driving pinion 34 are in mesh with the teeth 12 of the gear 10 and approaching the toothless sector 13, with the gear 10 turning counter-clockwise, the line of action of the tension spring 41 will have just passed below the axis of the shaft 9. Thus, it will be seen that as the meshing portions of the pinion 34 and the gear 10 approach the toothless sector 13, the spring 41 will become effective to impart a counter-clockwise torque to the gear 10, tending to continue rotation of said gear 10 in the same direction and as soon as the toothless sector 13 has been reached, the gear 10 will be rotated solely under the influence of the spring 41 until the abutment 21 engages the stop 24 at which time the parts will be in the position shown in Figure 4 of the drawings. In this position, the operating member 2 will have completed cock-

ing of the target trap and be in position whereby an additional movement to the left will release the trap mechanism. The length of the operating member 2 may be so adjusted, by sleeve 5, that in the stopped position described, release of the target projecting mechanism is just imminent.

The solenoid 29 is in an electrical circuit including a manually operable switch located at some convenient remote point, usually somewhere near the station from which a marksman shoots at projected targets. When the marksman is ready for the next shot, he will announce the fact and a designated person will momentarily close the switch referred to, thus completing the circuit through the solenoid windings which will move the armature 28 to the right (Fig. 2) and withdraw the stop 24 from the abutment element 21. As soon as the stop 24 has been so moved, the gear 10 will be free to rotate, under the influence of the tension spring 41, to move the toothless sector thereof past the pinion and bring the teeth of said gear into meshing relation with the pinion 34. As soon as such meshing relation is attained the rotating pinion 34 will assume control of the gear 10 and rotate it through one complete revolution until the toothless sector again comes opposite the pinion.

The operator of the solenoid switch will hold the switch closed only long enough for the abutment 21 to move past the stop position. He will then allow the switch to open, thus de-energizing the solenoid and allowing spring 26 to move stop 24 back into position to engage the abutment 21 when the latter has completed one cycle of rotation with gear 10. Obviously, if desired, the circuit including the solenoid may be provided with a timing mechanism whereby closing of the switch 54 will throw control of the solenoid circuit to the said timing mechanism, which latter will hold the circuit closed for a period of time sufficient for the abutment element 21 to pass clear of the stop element 24 and then automatically open said circuit to thereby release the stop element 24.

Immediately after the stop 24 is withdrawn from the path of the abutment 21, the gear 10, and consequently the crank arm 11 and operating member 2 will be given a rapid movement by the spring 41. It is this movement which occurs preliminary to the engaging of the teeth 12 with the pinion 34 that moves the operating member 2 sufficiently to the left to release the cocked spring mechanism of the target trap and the further rotation of the gear 10 by the pinion 34 will actuate the member 2 in a direction and to the extent necessary to re-cock the target trap.

When the stop 24 is withdrawn and the gear 10 released to the action of the spring 41, it often happens that the first tooth to approach meshing engagement with the pinion 34 will strike the end surface of one of the teeth of said pinion rather than pass smoothly into a space between pinion teeth. In such an event, breakage of either a gear tooth, or pinion tooth or both will follow unless some safety means are provided. The slidable carrier 31 on which the motor and pinion are mounted constitutes such a safety means.

In the event just described, improper engagement between teeth of the gear 10 and the pinion 34 will result in a reaction tending to push the pinion and gear apart and the spring 39 will allow the entire power assembly and its carrier 31

to move away from the gear 10 sufficiently to allow the teeth of the pinion and gear to assume proper meshing relationship.

Referring to Figure 3, which schematically indicates the circuits for the device of the present invention, numeral 50 indicates power lines through which electrical energy is supplied to the device and may, if desired, be provided with a master switch 51. The power lines 50 are connected to the terminals of the motor 32 and when the switch 51 is closed, the motor will commence operation and continue rotating until the switch 51 is again open. Also connected to the motor terminals are conductors 52 and 53. The conductor 52 extends from one motor terminal to a manually operable switch 54, which is the remotely located solenoid switch referred to above, and thence through conductor 55 to one end of the solenoid windings 56. From the other end of the solenoid windings, the conductor 57 connects with a safety fuse plug 58 which is in turn connected to the conductor 53. Thus, it will be seen that closing of the switch 44 will complete a circuit through the solenoid to effect withdrawal of the stop member 24.

While a specific embodiment of the invention has been shown and described herein, it is to be understood that various modifications may be resorted to and it is contemplated that all such modifications be included within the purview of this invention, limited only by the scope of the appended claims.

What is claimed is:

1. In a motion transmitting mechanism, a rotatable mutilated gear, a driving pinion therefor, stop means engageable with said gear to stop rotation thereof when said pinion is opposite the mid-portion of the toothless sector of said gear, means for temporarily withdrawing said stop means from engagement with said gear, and resilient means urging said gear to rotate past said stop means whereby when said stop means is withdrawn said gear will be rotated by said resilient means to move said toothless sector past said pinion and bring the teeth of said gear into mesh with said pinion.

2. In a motion transmitting mechanism, a rotatable mutilated gear, a driving pinion therefor, stop means engageable with said gear to stop rotation thereof when said pinion is opposite the mid-portion of the toothless sector of said gear, means for temporarily withdrawing said stop means from engagement with said gear, and resilient means urging said gear to rotate past said stop means whereby when said stop means is withdrawn said gear will be rotated to move said toothless sector past said pinion and bring the teeth of said gear into mesh with said pinion, said means for withdrawing said stop means comprising a solenoid connected to the said stop means to withdraw the same upon energization of said solenoid.

3. In a motion transmitting mechanism, a base, a mutilated gear rotatably mounted on said base, a crank arm fixed relative to said gear, a crank pin fixed to said crank arm, a second crank arm carried by said crank pin and adjustable about the axis thereof, a second crank pin on said second crank arm, a tension spring fixed at one end to said base and at the other end to said second crank pin, abutment means rotatable with said gear, stop means movably carried by said base for movement into and out of the path of movement of said abutment means, means normally urging said stop means into the path of said abutment, means for moving said stop means out of said path, a carrier movably mounted on said base for movement toward and from said gear along a path generally parallel to the plane of said gear, power means mounted on said carrier and including 10 a driving pinion in position to mesh with said gear, resilient means urging said carrier toward said gear, and stop means for limiting the movement of said carrier under the influence of said resilient means, the relative positions of the 15 parts being such that when the driving teeth of said pinion enter the toothless sector of said gear the line of action of said tension spring will be such as to continue rotation of said gear until said abutment engages said stop, at which time 20 said pinion will be opposite the mid-portion of said toothless sector, and when said stop means is withdrawn said tension spring will further rotate said gear to bring the teeth thereof into mesh with said pinion.
4. In a motion transmitting mechanism, a rotatable mutilated gear, a driving pinion therefor, positive stop means engageable with said gear to stop rotation thereof when said pinion is opposite the mid-portion of the toothless sector of said gear, and means urging said gear to rotate to a position to engage said stop means when said pinion enters said toothless sector, said last-named means comprising a tension spring attached at one end thereof to a crank 25 pin fixed relative to said gear.

ROBERT E. CLYNE.
